PIN SETTER FOR BOWLING ALLEYS

Rupert E. Rundell, Rockville Centre, N. Y., assignor to American Machine and Foundry Company, a corporation of New Jersey

Application December 18, 1941, Serial No. 423,458

59 Claims. (Cl. 273—43)

This invention relates to bowling pin setting machines and more particularly to improvements in mechanism for handling pins, and for setting and resetting them upon the bed of a bowling alley.

This invention relates generally to a bowling pin setting machine of the type shown in my co-pending application, Serial No. 260,901, filed March 10, 1939, for Bowling pin setters, in which bowling pins fall into the pit of a bowling alley and are lifted therefrom and delivered to mechanism which transfers them to a magazine wherein they are arranged for delivery to devices which transfer them from the magazine to positions above the alley bed corresponding to the playing position each will occupy when it is placed upon the alley.

It is an object of this invention to provide an improved control mechanism which may be of the general type shown in my co-pending application, Serial No. 400,164, filed June 28, 1941, for Bowling pin setting machine control mechanism, wherein certain sequential operations take place after the throwing of each ball depending upon the number of pins felled by each ball, and the condition of the alley bed after each ball is thrown. That is to say, if pins remain standing or if all pins are knocked down by the first ball, certain mechanisms operate to clear the alley of "deadwood" and set a new frame of pins on the alley bed, or if a "spare" is made, or pins remain standing after the throwing of the second ball, other selective mechanism is operated to effect the feed of a new frame of pins. While I have referred to my co-pending application as disclosing machines in which the subject matter of this invention is readily adaptable, it is within the contemplation of this invention to use my improved pin handling and setting mechanism on other machines with which it can be adapted.

According to the machine shown in my above referred to co-pending applications, there is provided a pin setting and resetting table which rotates at some time during the cycle of operation in order to position a new set of pins upright upon a bowling alley. This mechanism requires the use of separate sets of setting and resetting units which are located on opposite sides of the bowling pin setting table and are opposed thereto. The setters operate to spot a frame of pins, usually ten on the alley; the resetting units come into operation after the first ball has been thrown and are active in lifting and resetting any pins which remain standing after the throwing

of a ball in on or off-spot on the alley. According to my present invention I have eliminated the rotating type of setter-resetter table and utilize a table or elevator which is provided with units capable of performing the dual function of setting and resetting pins upon the alley bed.

This is brought about by the fact that instead of placing pins in inverted position in the resetter unit, I reinvert the bowling pins which are received butt end upward in my storage magazine, position them in conveyor cups or holding members, and transfer the pins handle ends upright into position where they are engaged and held by their respective setter-resetter units. Through relative movement between the units and cups, the pins are removed from the cups, transferred to the alley bed, and deposited thereon in proper playing arrangement.

In bowling pin setting machines it is always a problem to transfer pins expeditiously from the pit of a bowling alley to a setter and set the pins on the bowling alley bed in playing arrangement. Obviously, after a ball is thrown, there is some danger that pins remaining standing will "walk" or move to off-spot positions, therefore, whenever the alley is swept in order to clean it of "deadwood" after the throwing of a ball, it is necessary either to sweep all standing pins as well as "deadwood" from the alley or to lift standing pins and replace them in the exact on or off-spot position each occupied prior to the sweeping operation.

The mechanism disclosed in this invention relates more especially to a machine of the second type, and has for its basic thought the provision of a simpler pin setting mechanism in which upright pins are conveyed by individually and differentially movable pin supporting carriages to a point beneath a pin setting table, at which location, through relative movement between the pin setter table and carriages, the pins are transferred to the setter for delivery to the bowling alley in the desired predetermined playing positions thereon.

According to this invention I have also provided means for delivering pins butt end upward to a storage magazine which is arranged preferably to contain a sufficient number of pins to supply the needs of the setter in order to set the desired number of pins upon the alley. Usually ten pins are set in triangular formation upon the bed of an alley and, therefore, it is an object of this invention to provide means for setting ten pins in triangular formation upon the bed of a bowling alley and also to utilize the setting

means as the means for also resetting any pins which remain standing after a ball has been thrown, and insure the resetting of such pins in the exact position each occupied before it was lifted and the alley swept.

It is a further object of my invention to assemble a predetermined number of bowling pins butt end upward in a storage magazine and provide pin transfer members adjacent the storage magazine into which the pins are moved upward and located in upright position for delivery to a bowling pin setter which places them upon the bed of a bowling alley in predetermined playing arrangement.

It is an added object of my invention to provide pin transfer members adjacent the storage magazine into which the pins are delivered and located in upright position for delivery to the bowling pin setter which places them upon the bed of a bowling alley in predetermined playing arrangement and to furnish selectively operated mechanism to actuate the pin delivery means and the members with upright pins held therein whenever a new set of pins is to be placed upon the alley.

My invention also contemplates the provision of a bowling pin setter which is capable of receiving upright bowling pins delivered thereto from a storage magazine and which operates to place the pins in on-spot position on the alley wherein the setter is also operative to reset any pins remaining standing after the throwing of the first ball in the exact position each occupied before the removal of "deadwood."

It is a further object of my invention to provide a vertically movable setter table having thereon a single set of floating setting and resetting units which coact with a series of differentially movable bowling pin holding cups to receive and hold upright pins delivered to the setter units by the cups and effect a relative movement between the table and cups so that the pins can be set in on-spot position prior to the throwing of the first ball and which units are operative to reset any standing pins upon the bed of the alley in the exact position, on or off-spot, each occupied after the throwing of the first ball.

My invention also consists in the provision of mechanism for aligning a plurality of bowling pins in a number sufficient to satisfy the requirement for a given frame, invert the required number of pins into an aligned series of pin receiving and transferring cups operative to deliver the upright pins in substantial playing position to a pin setter which deposits the pins in playing arrangement on the bed of a bowling alley.

It is a further object of my invention to provide an improved control mechanism for use in effecting completely automatic control of the several units which cooperate to set and reset pins in accordance with the number of pins felled by the first and second balls of each frame of the game and without manual intervention of the player.

It is a further object of my invention to provide improved automatic control mechanism for effecting the feed of inverted pins from a magazine into upright position in members which transfer them into substantially triangular position above a bowling alley for delivery thereto in playing arrangement.

An added object of my invention is to provide a bowling pin setting table having a plurality of movable units capable of performing the dual function of setting and resetting pins upon the bed of a bowling alley, which units cooperate

with a plurality of pin holding cups having differential movements so that whenever pins are to be transferred to the setter units, the latter are properly positioned on the pin setter table because of the relative lateral movement set up between the units and the cups, and wherein the setter-resetter units are so designed that they are capable of lateral movement on the setter table, which means that if any pins occupy an off-spot position after throwing of the first ball, the setter-resetter units will be moved by engagement with the handle end of the standing pins so that the disposition of the units relative to the standing pins is such that the return of these pins to precise off-spot or on-spot position is insured at all times. So also, if any or all of the setter-resetter units are moved out of proper alignment, usually triangular, as the bowling game is now played, then through coaction with the handle ends of a set of pins held in the conveying cups for delivery to the setter-resetter units, the units will be moved laterally into exact triangular formation prior to the release of the new set of pins from the delivery cups and, therefore, they will be properly positioned in playing arrangement upon the alley bed awaiting the throwing of the first ball of the next frame.

With these and other objects not specifically mentioned, in view, the invention consists of the combinations and constructions which will be hereinafter fully described, and then set forth in the claims hereunto appended.

With these and other objects not specifically mentioned in view, the invention consists in certain combinations and constructions which will be hereinafter fully described, and then set forth in the claims hereunto appended.

Figure 13 is a partial cross-sectional plan view showing the detail construction of a part of the

structure control mechanism taken on line 13-13 of Figure 9; and

Figure 14 is a diagrammatic and schematic wiring diagram.

Referring to the drawings, and more particularly to Figures 1 to 4, inclusive, which show a preferred embodiment of my invention, the frame of the machine consists of vertical standards 1 joined by side connecting members 5 and 7 and transversely connecting members 3. A motor bracket support member 9 extends transversely across the rear of the machine and is suitably secured to frame member 1 as shown in Figures 1 and 2, for supporting motor DM which provides the drive for the machine through a suitable reduction gearing of any well known type having a drive shaft 11 which transfers the drive through a sprocket 13 on shaft 11 and chain 14 to sprocket 15 loosely mounted on shaft 19 journaled in side frames 7.

The construction of my machine may conform in part with that shown and described in my co-pending application, Serial No. 260,901, for Bowling pin setter, filed March 10, 1939, in which a ball B arriving in pit P at the end of an alley falls upon a pin and ball elevator 2 (Figure 2) which may take the form of that shown in co-pending application, Serial No. 323,063, filed March 9, 1940, by Gustaf Hagquist, movable vertically into and out of the pit in order to return the ball to the player and discharge the pins back of a bumper 4 hung at 16 on a support 8 into a pin receiving chamber C from which the pins are elevated and distributed by mechanism similar to that shown in the above referred to application. The arrival of a ball B in the pit causes a switch control member 10 located beneath the pin and ball elevator to close a switch 12 and energize a clutch of any suitable type, such as a Bliss clutch 17 (Figure 1) mounted on shaft 19 to transfer the drive from shaft 11 to shaft 19 for controlling the operative sequences of the pin handling and setting mechanisms, in the same general manner as described in said application, Serial No. 260,901.

When clutch 17 is energized and shaft 19 is set into rotation at the proper time, the drive is transferred by means of a sprocket 21 fast on shaft 19 through chain 23 to sprocket 25 secured to cam shaft 27, and in this manner cam 29, having a cam track 30, either integral with or fastened to sprocket 25, is rotated at the proper time and thereby controls the movement of the pin setter table T, as described hereinafter. Cam 30 is formed with a high portion 30a; a low portion 30b; a high portion 30c; a low portion 30d; a high portion 30e; and a low portion 30f. This cam is responsible for the movement of table T in setting and resetting pins. Cam shaft 21 is suitably mounted in bearings in side frame members 6 secured to longitudinal frame members 5 and 7 (see Figures 2, 3 and 4).

Loosely mounted on shaft 19 between collars 33 is a sprocket 31 which has associated therewith a suitable clutch 35, preferably of the Bliss type, which is adapted at the proper time to connect sprocket 31 to drive shaft 19 in order to drive cam 41 on cam shaft 27 and thereby impart movement to the mechanism which is responsible for transferring pins from magazine M (Figure 2) into individual pin conveying members or cups 101, described in detail hereinafter. As shown in Figure 1, a chain 37 tracking sprocket 31 drives sprocket 39, either integral with or fastened to cam 41 provided with a track 42.

Cam 41 is loose on cam shaft 27 and is positioned between collars 43 fastened thereon.

Mounted on shaft 19 is another loose sprocket 45 having associated therewith a suitable clutch 47 preferably of the Bliss type, by means of which the drive of shaft 19 is transferred by means of sprocket chain 49 to sprocket 51 secured to or integral with a cam 53. Collar 55 fixed to shaft 27 locates sprocket 51 and cam 53 in proper working relationship with sprocket 45. It will be seen from the above that cams 41 and 53 are not operative until clutch 17 has connected sprocket 15 to shaft 19 for driving the same and either one or both of the clutches 35 and 47 have been energized to transfer the drive from shaft 19 to sprockets 39 and 51, respectively.

Pivoted on shaft 59 journaled in bearings in side frame members 7 is a lever 57 provided with a cam follower 61 tracking cam track 30 on cam 29. The free end of lever 57 is connected to a link 63 pivotally joined at 64 to a rack 65 which is guided in a slot 66 in bracket 67 fastened to top longitudinal frame member 5.

Rack 65 meshes with pinion 69 fast on shaft 71 suitably mounted in bearings in side frames 5 upon which are fastened pulleys or sheaves 75. I prefer to use two sheaves located adjacent the ends of shaft 71. These sheaves are of a well-known type having a peripheral groove upon which is wound and unwound a cable 77 fastened at 79 to the sheave. The other end of the cable is secured to a slide portion 18 of the pin setter table T in order that the table may be raised and lowered at proper intervals. As shown in Figure 2, the table is raised to its uppermost position, due to the retraction of lever 57.

As will be seen in Figure 1, slide portions 18 travel in guides 80 mounted on vertical standards 1 and direct the movement of the table to and from the alley bed for setting and resetting pins thereon. Table T preferably is of the same general type and construction as that described in my co-pending application, Serial No. 400,164, filed June 28, 1941, for Bowling pin setting machine control mechanism, in which there is provided a plurality of suction pin holding units 82 slidably mounted by contact with the handle end of pins on a table plate 84 provided with openings spaced generally in triangular formation so that the handle end of pins can project upwardly through the openings (not shown) in the table plate 84 and into the pin holding units 82. The plate 84 is supported by means of rods 85 on a generally triangularly shaped member 83 fastened to the frame 88 of the table. The pin holding or gripping units 82 are preferably operated by suction, as in the case of the similar units shown in my co-pending application, Serial No. 400,164, and receive their suction at proper times through a conduit 87 fixed to a valve V (Figure 1) mounted on the side of the machine and extending to a suction distributing conduit system 88 having an outlet above each of the pin setting and resetting holders 82. These units are also provided with electrical switches 81 (Figure 14) which are connected in a series circuit including each of the suction holders for reasons to be described hereinafter.

The suction may be obtained from any suitable source but generally is created by means of a fan (not shown) driven from the continuously operated motor DM and the control of suction in the holders 82 is effected by means of shaft 27 having fixed thereon a sprocket 89 (Figure 1) with which coacts a sprocket chain 90 tracking

a sprocket 81 on a control operating shaft 92, as described hereinafter.

It will be evident from a reference to Figures 1 and 2 that the suction holders 82 perform the dual function of setting and resetting pins upon an alley. That is, whenever pins are standing on the alley and a ball is thrown and all pins are knocked down or a "strike" is made, the alley will be guarded against further ball throwing and swept by suitable means (not shown) and the table will be lowered to cause the holding units 82 to locate a new frame of pins on the alley in on-spot position, whereupon the pins are released from the holders and the table rises to inoperative position above the alley. If all of the pins are not knocked down by the first ball thrown, the guard and sweep will move into operative coaction with the alley, the table will be lowered again and the same units 82 will perform the function of resetting the pins since they are operative to lift the standing pins so that the sweeping operation can be performed by means (not shown), after which the table with the lifted pins is again lowered and the pins, because of the fact that each setter-resetter pin holding unit 82 is individually movable on plate 84, will be returned to its exact on or off-spot position, released and the table rises so that the second ball can be thrown. Suitable guard and sweep mechanism, such as that shown in my Patent No. 2,250,503, granted July 29, 1941, may be employed for sweeping and guarding the alley against undesired or carelessly thrown balls while the setting and resetting operations are taking place.

In the case of a "strike" the arrival of a ball in the pit P of the alley effects the operation of one-revolution clutch 17, as described hereinabove, and rotates cam 30 through 360° to carry out the various movements of the table necessary to setting a new frame of pins on the alley. Referring to Figure 2, cam follower 61 on lever 57 connected by means of link 63 to rack bar 65 as it travels along the surface of cam 30 from high portion 30a to low portion 30b by means 45 of pinion 69 and sheaves 75 and cables 77, causes table T to be lowered as the lever 57 swings to the right (Figure 2) whereupon table T is positioned adjacent the alley. The table is then raised to its upper limit as follower 61 travels 50 along and onto high portion 30c of cam 30, at which time lever 57 is swung in an opposite direction to rotate sheaves 75 and wind cables 77 thereon. While table T is held in its uppermost position (Figure 2) pin transfer cups 101, described more in detail hereinafter, holding a set of pins move into triangular arrangement beneath the pin setting units 82 on table T and locate the pins therebeneath for delivery to the units 82. The continued rotation of cam 30 55 causes low part 30d to be engaged by follower 61 and table T is thereby lowered a distance sufficient to allow the pins in cups 101 to be positioned in the gripper units 82. Suction is then created in the units 82, as described hereinafter, 60 the pins are gripped and lifted thereby, then table T is raised as the follower 61 travels onto high portion 30e to clear the pins of cups 101 which thereupon return to their original pin receiving positions adjacent magazine M. Continued rotation of cam 30 causes the follower 61 to travel onto low portion 30f and as a result of this movement, lever 57 swings to the right (Figure 2) to lower the table to its lowermost position in which the pins are located on the alley. 75

Suction is cut off and the pins carried by units 82 are freed therefrom whereupon as follower 61 travels up high portion 30a, the table T is again raised to its uppermost position, as shown in full lines in Figure 2, leaving the newly set pins standing on the alley. One revolution clutch 17 then becomes inoperative and the table dwells awaiting further play. The movement of table T to and from the alley after the throwing of a ball is the same regardless of the number of pins knocked down by each ball thrown. Control of suction, as described in detail hereinafter, will vary however depending upon the number of pins knocked down by the first ball thrown so that if a "strike" is made, a full set of pins will be set, or if less than ten pins are knocked down by the first ball, the remaining pins will be lifted and reset, and in any event after the last ball allowed by a frame has been thrown, a new set of pins will be positioned on the alley. In short, the table is lowered and raised twice after each ball is thrown.

As stated above, the pin handling and distributing mechanism, which is responsible for the movement of pins from the chamber C located at the rear of the pit P (Figure 2) to the spirals 96, can be of the same general construction as that shown and described in my co-pending application, Serial No. 260,901, above referred to, in which pins are conveyed from chamber C back of bumper 4, inverted and fed butt end upward by conveyor 93 moving on guide pulley 95 along curved guide rails 94 and onto pin assembling members, such as rotating elongated spirals 96, 35 preferably both of the same hand and rotating in the same direction, which translate pins therealong, whereupon the first pin strikes against wall 87 which acts as a suitable stop, and the other pins form an aligned series abutting against each other in vertical arrangement butt end upward. As will be evident from Figure 1, eleven pins are aligned so that there is always in the magazine a sufficient number of pins for meeting the requirements of the game. Usually ten pins constitute a frame, and therefore, until there are at least ten pins on the spirals 96, pins will continue to be furnished by conveyor 93 until the magazine is full or until all of the individual pin control switches 98 are closed and a circuit completed, at which time the ball has been returned to the player and the guard and sweep mechanism have been removed from the alley and the electrically operated clutch 17 is disconnected from shaft 19 which ceases to rotate.

The pins (as shown in Figure 1) rest on spirals 96 in an aligned row or series, butt end upward, and so long as there is a full magazine of pins, the machine will operate in the manner set forth above, as soon as a ball lands in pit P.

In setting a new frame of pins on an alley, therefore, it is necessary that pins obtained from the magazine or from the spirals 96, be turned 180° in order that the pin holders 82 on the pin setters may be able to grip the handle ends thereof for positioning the pins on the alley when the table with its load of pins is lowered. A preferred form of my novel pin turning and handling mechanism is shown in Figures 1 and 2. Mounted on support rods 99 carried by frame member 7, is an inverted U-shaped guiding chute 100 so positioned that when pins are lifted upward, the butt ends engage the curved portion of the chute, slide therealong through 180° (as shown by the arrow in Figure 2) and fall by

gravity into a plurality of conveyors 101 positioned in an aligned series therebeneath and seat themselves therein, handle end upright for delivery to the holders 82 of the pin setter table T. It is desirable that the means which receive pins from the turning devices be positioned relatively close to the magazine in order that space may be saved and as simple a machine as possible be constructed. As shown in Figure 2, the conveyors 101 are located adjacent the discharge end of the guide chute and are positioned so that the pins may fall thereinto by gravity and at the same time there is sufficient space for allowing the conveyor to move beneath the table and back to retracted position without interfering with the movement of the table.

The turning device employed may be formed in any suitable manner, such as by shaping it out of sheet metal. In the embodiment shown, chute 100 is provided with inwardly projecting integral portions or vanes 103 conforming to the general shape of the chute which serve in guiding pins properly into conveyors 101. As shown in Figures 1 and 2, the head ends of pins positioned butt ends upward on spirals 96 rest upon a pin turner 105 provided with an upstanding portion 107 which coacts with a fixed vertical wall 108 spaced from portion 107 a distance greater than the maximum diameter of a pin head and assists in the delivery of pins along the spirals as they are being assembled in filling the magazine by preventing the heads from unnecessary swinging back and forth as they move along the spirals 96.

An auxiliary guide member 111 mounted on suitably supported rods 113 may be used as an aid in the turning and delivering of pins to the conveyors 101. The outer face of the chute 100 is provided with spaced openings 102 through which the heads of upright pins held in cups 101 move in their travel to the setter-resetters 82.

Pin turner 105 preferably is curved in order to conform with the shape of the pin handle ends. This member also assists in maintaining the assembly of pins 20 vertical, in butt end upright arrangement for proper disposition for turning and delivery to cups 101. This is because the member 105 acts as a transverse stop and prevents non-uniform elevation of the pins on the spirals 96.

The pin turner 105 is mounted for movement to project pins through guiding chute 100 by any suitable means, such for instance as a vertically movable horizontal bar 115 secured at its ends to bars 117 (Figures 1, 2 and 4) vertically slidable in guides 118 fixed to the side frame members of the machine. Levers 119, preferably fixed to the ends of shaft 123 mounted in bearings 125 fixed to frame members 5, are connected to links 121 and move the turner 105 up and down whenever cam 41 rotates. This causes a cam follower 127 on lever 129 fixed to shaft 123 to rock lever 119 and hence move the turner.

The mechanism for operating the conveyor cups 101 is shown in Figures 5, 6, 7 and 8. In Figure 5 it will be seen that two spaced supports 131, 132 extend between side frame members 1a and support the conveyor system. The system comprises ten cups 101 preferably provided with upstanding flanges 104 and active in assisting and positioning the butt ends of pins for transfer from the pin receiving position adjacent the discharge end of the turning chute 100 to a delivering station beneath the pin setter table T. Each of the ten cups 101 has an individual and differential movement in order that pins can be moved from

5 a row into substantially triangular formation beneath the pin setter table for delivery to the triangularly arranged pin holder units 82. Obviously, if any other pin playing arrangement were desired, suitable modifications can be made. The mechanisms for operating each of the cups is the same and hence only one will be described in detail. Each cup is provided with a rack 133 having a cup 101 mounted on the free end thereof and projecting upwardly towards the discharge end of the turning chute 100 when the cups or conveyors are in retracted position. Each rack 133 is provided with side grooves 135 in which run guide rollers 137, 138 carried by roller supports 141 fixed by screws to cross supports 131 and 132. A reference to Figure 5 will show that the length of the rack bars 131, 133 varies in accordance with the amount of travel each conveyor 101 must make in moving from aligned position to that necessary to deposit the pins in triangular formation (as shown in dotted lines in Figure 5). That is, the conveyor cup, which transfers pin No. I travels a greater distance than the conveyor cup VII, which delivers pin No. VII to its designated location beneath the pin setter table, and so on. As shown in Figures 2 and 6, each cup 101 is mounted on top of and at the forward end of a rack 133 with the bottom cup rim projecting beyond the sides of the rack (see Figure 5). This construction insures proper operation of the cups relative to and past each other at all times. Movement of the conveyor cups is effected from transverse shaft 143 which is provided with ten sprockets designated generally 145 of varying diameters. This relationship is necessary in order that certain of the cups will move with greater speed so as to complete the movement of all of the cups into triangular formation at substantially the same time. The rotation of shaft 143 and the ten sprockets 145 is transferred through ten chains 147 to ten other sprockets 148, each secured to a gear 150 engaging with a rack 133 mentioned heretofore. Referring to Figures 5 and 6, it will be seen that sprocket 145a controlling the movement of cups 101 holding pin No. I is the largest; sprockets 145b which operate cups 101 holding pins II and III are next largest; sprockets 145c operating cups 101 holding pins V and VI are next in size; and sprockets 145d which move cups 101 containing pins VII to X, inclusive, are smallest. The relationship between these driving means is such that all pins are moved to proper positions without any cup or rack interference during the travel thereof. For instance, cups 101 holding pin I, which travels the greatest distance, moves most rapidly to its No. I position in the triangular pin arrangement, as shown in dotted lines in Figure 5. Cup 101 carrying pin No. V moves more slowly to its final position and, as shown in Figure 5, when all cups are positioned finally for delivery of pins to setter units 82, the rim of cup 101 holding pin V will overlie rack 133 which supports No. I pin holding cup 101. Sprockets 145 and gears 150 are loosely mounted on shaft 151 and each pair is positioned between collars 144 fastened to shaft 151. Shaft 151 is supported by brackets 153 fixed to cross support 131. At one end of shaft 143 is mounted a pinion 154 which meshes with a rack 155 connected by a link 157 to lever 159 fulcrumed on shaft 59. Lever 159 is provided with a cam follower 161 operable in a cam track 163 of cam 53 loosely mounted on shaft 21 so that at the proper time when pins are to be fed to the 75 pin setter through clutch 41, cam 165 is rotated

and rack 155 is reciprocated to effect the individual and differential movement of the conveyors in their delivery of pins to the setters.

Figures 9, 10, 11, 12 and 13, disclose in detail a preferred form of control device for effecting selective and automatic operation of my improved pin setter wherein all phases of setting, resetting the same pins, after a ball has been thrown, in on or off-spot positions, removal of "deadwood," or other related, allied or sequential operations are accomplished entirely without manual intervention of the player. The control mechanisms are actuated by means of shaft 92 driven in a manner described heretofore. The shaft 92 is mounted in suitable bearings of a housing 201 supported by a bracket 202 mounted on one of the frame members 1 of the pin setter machine. On shaft 92 is mounted a gear 203 and a gear 204. Gear 203 meshes with a gear 205 secured to a shaft 206 while gear 204 meshes with a gear 207 loosely mounted on a stud 208 held by housing 201. To the hub of gear 207 is attached another gear 208 (Figure 9) which meshes with a gear 210 also loosely supported by a stud 211 held by housing 201. Gear 210 meshes with a gear 212 which may be provided with a hub 213 designed to provide a support for four spring mounted plungers 214, each of which can be locked and released by means of a co-operating bell crank shaped pawl 215 which engages or disengages from its corresponding recess 216 of its corresponding stem 217 with which each plunger 214 is equipped. Hub 213 of gear 212 is loosely mounted on a stud 218 fastened to the housing 201. The ratio of the gears just described is so selected as to effect the following results: While the main cam shaft 27 makes one revolution, the shaft 92 will make two, shaft 206 will make one-half, and gear 212 and hub 213 will make one-quarter revolution.

On shaft 206, by means of a key 220 (Figures 10 and 12), is slidably mounted a hub or sleeve 221 provided with three suction control cams 222, 223 and 224, a strike control cam 225, and also two spare control cams 226 and 227. The several cams can either constitute an integral part of hub 221 or be secured thereto in any known manner. As shown, cams 222, 223 and 224 are separate members fixed to the hub, whereas cams 225, 226 and 227 are integral parts thereof. The lateral movement of the control unit, which includes hub 221 and all cams just described, is effected by means of a cam lever 228 provided with a follower, such as a roller 229, which engages with a groove or track 230 in hub 221. A tension spring 231 placed between a stationary collar 232 on shaft 206 and the end of hub 221 formed by cam 227 is employed to keep all cams in their proper horizontal position. From the hub of cam lever 228, which is mounted on a vertical stud 233, extends another arm 234 which carries a roller 235 engaging with a forked portion 236 of a cam arm 237 attached to a lug 238 pivoted to a stud 239 held by housing 201. The vertical stud 233 is supported by a bearing bracket 240 mounted on a bridge bracket 241 attached to housing 201. The latter, furthermore, carries a stud 242 on which is pivoted a star wheel 243 having secured thereto a star cam 244. On star cam 244 rides a cam follower 245 mounted on a lever 246 pivoted to a stud 247 held by a suitable lug of housing 201. From the hub of lever 246 extends another arm 248, the end 249 of which consists of an angular extension or hook. A tension spring 250 suitably connected

5 at one end to bracket 241 and at the other to an arm 246a of lever 246 is provided to maintain follower 245 in contact with cam 244. In order to prevent possible spinning or overrunning of star wheel 243 and assure a point by point movement during operation of the machine, a flat suitably shaped contact spring 251 engages the star wheel (Figure 9) and locks it against unwanted movement.

10 The upper portion of housing 201 carries a suction control housing 252 which is provided with an inlet 253 and an outlet 254. Inlet 253, by means of a hose 250, is connected to any suitable source of suction, while the outlet 254 is connected to the suction distributing conduit system 88 of pin setter table T by means of the flexible hose or conduit 87. Within housing 252 is slidably mounted a valve 255, which in its uppermost position (Figure 11) causes the suction to be directed to the pin setter table, while in its lowermost position (Figure 11) the suction intake 253 is shut off and the suction in the pin setter table and adjoining conduits bleeds to the atmosphere through a passage 256 in valve 255 and an opening 257 on top of suction housing 252. Suction valve 255 is operated by means of a lever 258 (Figure 9) having a portion thereof extending through a slot 259 and engaging a pin 260. Lever 258 is pivoted to a stud 261 held by a suitable bearing bracket 262, and is operated by either one of the three suction cams 222, 223 or 224, depending upon which cam happens to be positioned for coaction with lever 258 in accordance with the selective operation of the machine. Lever 258 is also equipped with an extension 263 engaging an adjustable stop screw 264 in order to keep a projection 265 of lever 258 slightly off the low portion of cams 222, 223 and 224 and thereby insure shifting of the cams in a horizontal direction without interference and locating the proper cam relative to projection 265. The selected cam then moves suction valve 255 to supply suction to the pin setter table T, as described heretofore. A tension spring 266 is provided to maintain valve 255 in constant contact with its operating lever 258.

45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

Mounted on housing 201 is a bracket 267, which supports a control solenoid 268 and a switch control 269. The latter preferably consists of a push button switch and is operated by an arm 270 mounted on a shaft 271 supported by a suitable bracket 273. Also, fast on shaft 271 is a lever 272 provided with a cam follower 272a arranged to coact with cams 226, 227 for swinging lever 272 into engagement with switch control 269 whenever a bump on the selected cam of the two spare cams 226 and 227 is engaged thereby.

An extension 274 of the armature of control solenoid 268 is connected to one arm of a bell crank lever 275 while the other arm of this lever is provided with an angular extension, preferably a segmentally shaped lug 276 which, depending on the action of solenoid 268, is moved into or out of the path of the operating pawls 215 of plungers 214 rotating with hub 213 of gear 212, described heretofore. Bell crank lever 275 is pivoted to a stud 277 held by bearing bracket 240.

In an automatic pin setter, such as described herein, there are usually two different conditions which must be contended with, namely: (1) a first and second, or "spare" ball, which "spare" ball knocks over all pins remaining standing on the alley after the first ball of a frame has been thrown; and (2) a first or "strike" ball, which knocks down all pins. Figure 14 discloses in a

diagrammatic and schematic form the several electrical elements and their connection to the circuit employed in this invention with L_1 and L_2 being the power lines as the source of current.

The operation of my novel pin setting machine is as follows: Assuming that the machine is ready for action, meaning that the motor DM is running and ten pins are positioned in the customary playing arrangement on the bowling alley, the player throws the first ball down the alley and the ball knocks down only a few of the ten pins standing before it lands in the pit P. The weight of the ball B closes the switch 12, and if ten pins are in the magazine M, all of the individual magazine pin control switches 98 are closed so that a suitable circuit (Figure 14) is closed and causes energization of a solenoid 11a which operates and engages the clutch 17 of sprocket 15 thus causing the shaft 19 (Figure 1) to be driven by sprocket 15 from the motor DM. Since the table operating cam 29 is fast on shaft 27, which is driven by shaft 19 through sprocket 21, chain 23 and sprocket 25, the table T descends immediately, the setter-resetter units 82 on the table are energized and pick up the remaining pins standing on the alley whereupon the table T ascends with the lifted pins held in the units 82 while the fallen pins or "deadwood" are swept off the alley in the manner above mentioned.

Each time a ball is thrown it is returned to the player by any suitable means (not shown) but which, however, may be of the same general type as that shown in co-pending application, Serial No. 323,062, filed March 9, 1940, by Gustaf E. Hagquist, now Patent No. 2,293,018, issued August 11, 1942, for Pit elevator for bowling pin setting machines. The pins also are removed from the pit at the proper time and distributed by means of the type shown in the above referred to co-pending application, Serial No. 260,901, and positioned butt end upward in magazine M.

It will be noted by a reference to Figure 2 that the setter-resetter units 82 may be of the same general construction as shown in my co-pending application, Serial No. 400,164, and that each unit is mounted for individual lateral or sliding movement on apertured plate 84 which forms part of the table mechanism T, and also for vertical movement relative to plate 83 so that when pins are located in units 82 for gripping by means of suction locking rings 82a carried on the upper portion of each unit 82, each unit will be held fixed to plate 83 until the suction under control of valve V is cut off whereupon pins are freed from the units, and the latter become disengaged from plate 83. By means of this construction I have made it possible to utilize units 82 for setting pins of a frame on the alley in on-spot playing position prior to the throwing of the first ball and also for resetting any pins remaining standing after the throwing of a given ball of a frame in the exact on or off-spot position each occupied prior to its removal from the alley for sweeping purposes. It will be seen, therefore, that units 82 are designed to perform at least two positive pin handling functions depending upon the number of pins knocked down by each ball of a given frame. Therefore, if any of the pins of a frame remain standing after the throwing of a ball and one or more have "walked" from their original spotted positions, when the table T is lowered to bring the setter-resetter units 82 into engagement with the handles of the standing pins, the units 82 which correspond to off-spot positions, will be shifted laterally or slid along plate

84 into alignment with the off-spot pins so that when the units are energized to grip and lift the standing pins, the positions of the setters will correspond to the off-spot positions of the pins due to the coaction between rings 82a and table 83, and hence when these pins are reset they will be returned to their identical off-spot positions.

Following the sweeping of the alley, the table T then descends and the pins which were lifted are released by units 82 which are de-energized when the butts of the pins engage the alley and are replaced on the alley in the same on or off-spot position each occupied before being lifted. The table then ascends, with suction cut off, immediately. As mentioned heretofore, the pins are picked up by suction operated units 82, controlled by the suction valve 255 (Figures 9, 10 and 11) and operated, at this particular moment, by the cam 224 which is considered a "spare" cam. As described hereinbefore, cam 224 is rotated by shaft 206 driven through gears 205 and 203 from the sprocket 81, which through chain 90 and sprocket 87 is connected with shaft 27 so that as soon as shaft 27 is driven, the control cam shaft 206 is actuated, the ratio being such that shaft 206 makes one-half revolution to every one revolution of shaft 27. The reason for this design is that during the second half of the cycle of the machine, that is, after the second ball is thrown, no suction is desired, and since valve operating lever 258 in this instance will stay above cam 224, the second half of the periphery of this cam is designed accordingly.

After the pins have been reset, as described above, the player throws a second ball and knocks down all or only some of the pins which remained standing after the first ball. The ball, of course, again lands in the pit and assuming that all switches 98 in the magazine are still closed, the closing of the pit switch 12 again will cause the energization of solenoid 11a, and re-engage clutch 17 to effect the drive of shafts 19 and 27 in the manner mentioned above. The table T descends again, but since there is no suction supplied during the second half of the cycle of the machine, the setter-resetter units 82 on table T will not pick up any pins in case some are still standing and hence the table rises empty while the alley is swept clean of all pins. In the meantime, a bump on cam 227 fast on shaft 206 has lifted lever 272 thereby causing arm 270 to press against push button 269, make a suitable circuit (Figure 14), and energize solenoids 35a and 47a, which causes the latter to engage clutch 47 while the former engages clutch 35. As mentioned hereinbefore, clutch 35 effects the operation of the pin turning mechanism, and clutch 47 actuates the pin delivering mechanism which supports cups 101. Therefore, as soon as solenoids 35a, 47a are energized, the ten pins held by spirals 96 in the magazine M are moved out of the magazine by means of turner 105, and conveyed through guides 100 into conveyor cups 101, each of which is mounted on a rack 133 in the described manner, the pins being delivered handle up into said cups. As soon as table T, moving up from the alley bed, has reached its uppermost position, the conveyor cups 101 with the upright pins held therein preferably are moved severally and differentially in the direction indicated by an arrow Y (Figure 2) to locate the pins held therein in substantially triangular arrangement underneath the table T. The table descends the distance necessary for the units 82 to contact the pins in cups 101 and the

relative movement between conveyors 101 and table T causes units 82, which engage the handle ends of pins in conveyors 101 to be lifted, and by means of valve V suction is then created in units 82 which then grip the pins so that when relative separating movement is instituted between the table T and conveyors 101, as when the table ascends a sufficient distance, the pins are withdrawn from cups 101 and the latter return to their original positions near the magazine M (Figure 2). It will be evident that if any of the units 82 are not positioned in exact triangular arrangement, they will be properly aligned when the handle ends of pins held in cups 101 engage the downwardly flaring portions of the units 82 and shift them into proper positions. The relative movement between table T and the triangularly arranged cups 101 causes units 82 to be lifted against plate 83, and because of the action of suction then operative in the system, the units are sealed to plate 83 in proper arrangement and the several pins constituting a new frame are gripped and held in proper triangular arrangement for removal from the cups 101 for delivery to the alley.

With each of the ten units 82 holding a pin, table T again descends and places the new set of pins in their proper onspot playing positions on the alley, the suction to holders 82 on table T is shut off substantially as soon as the pins engage the alley thereby releasing them from holders 82 after which the table T again ascends to its uppermost position. In the meantime magazine M is filled again with ten pins by means of the conveyor 93 and spirals 96 in a manner similar to that shown in my co-pending application, hereinabove mentioned.

With ten pins standing on the alley and ten pins in the magazine M, the machine is now ready for the player to throw the first ball of his next frame. Assuming that the player throws his first ball down the alley and makes a "strike," that is, all the pins are knocked down by the first ball which lands in the pit thereby closing pit switch 12 and together with switches 98 close the circuit. Solenoid 17a causes the engagement of clutch 17 thereby starting the machine. Table T descends again with the suction in holders 82 on, as always after the first ball is thrown (first half cycle of the machine). Since all the pins are knocked down by the first ball and the suction valves in the pin holders 82 cannot contact any pins, these valves, as disclosed in my previous application, Serial No. 400,164, cause the closing of switches 81 each of which is located in one of the pin holders 82. Switches 81 are connected in a series circuit, one end of which is connected to the strike control solenoid 268 while the other end leads to a sliding switch 300 (Figures 1 and 14) fastened to a convenient place on the frame 86 of the table T and, of course, ascending and descending with the table. Switch 300 makes contact with the power line L₂ only when sliding onto or resting upon a suitable contact plate 302 which is suitably mounted on one of the vertical standards 4 of the machine. Plate 302 is so located that switch 300 can only contact the same when the table is in its lowermost position above the alley.

Since all pins were knocked down by the first ball and the suction valves in the table closed all switches 81 when table T was lowered thereby making a suitable circuit and energizing strike control solenoid 268 which is responsible for moving the segmental portion 276 of bell crank lever

275 pulled by armature 274 into the path of one of the pawls 215 revolving with hub 213 of gear 212. The latter, as previously mentioned, is so constructed that it makes one-quarter revolution to one revolution of shaft 27 or 90° of that of the table cam 29. This ratio is so selected that no more than one pawl 215 or plunger 214 can move into operating position during any one frame of a game. When portion 276 of lever 275 swings into the path of pawls 215, as mentioned above, it knocks one of the pawls 215 out of engagement with its corresponding recess 216 of its corresponding stem 217, and due to the action of a spring 211a causes the corresponding plunger 214 (Figure 13) to protrude from hub 213. The protruding end of this selected plunger, still traveling with hub 213 in the direction indicated by an arrow in Figure 9, will then engage with the edge of cam arm 237 and press the same while sliding along its edge in the direction of the arrow indicated in Figure 9. Since roller 235 pivoted to arm 234 engages with the forked upper portion 236 of arm 237, this movement will be transmitted to arm 228 and roller 229 which tracks groove 230 of hub 221 to which all suction control as well as the two "spare" and one "strike" cams are mounted. This movement causes the cams, which together with hub 221 form one unit to shift in the direction of the arrow 2 (indicated in Figure 12) and are held while rotating with shaft 206 in such a position that the strike suction control cam 222 is underneath the suction valve operating lever 258 and the strike cam 225 is underneath the push button operating lever 272. Strike cam 225 has no bumps and, therefore, cannot actuate the push button 269 which in turn would effect the operation of the pin turning and delivering mechanisms, but since it is necessary to effect such an operation in order to place a new set of pins on the alley by the descending table after a strike is made, a switch plate 304 (Figure 14) mounted on an extension 274a of armature 274 of solenoid 268 makes a desired contact and closes a suitable circuit necessary to energize solenoids 35a and 47a, effecting the engagement of clutches 35 and 47 which operate the pin turning and delivering mechanisms, respectively. Therefore, the ten pins in the magazine M are up-ended and delivered into cups 101 which as soon as the table T has reached its uppermost position, convey them to their proper position therebeneath. The table then descends, units 82 pick up said pins and ascends to permit the retreat of the empty cups 101 after which the table with the pins descends again and places the latter in the proper playing position on the alley, which of course in the meantime was swept clean of the fallen pins. After depositing the pins on the alley, the table T ascends again to its uppermost position, the magazine M is filled again with ten pins, and the machine is ready for another frame.

As mentioned heretofore, the protruding plunger 214 by sliding along the edge of cam arm 237 moves the latter sideways and shifts cams 222, 223, 224 and 225, 226, 227 thereby bringing the strike cams 222 and 225 underneath the suction operating lever 258 and push button operating lever 272, respectively. In order to be ready for the unknown outcome of the next play it is necessary after a "strike" is made to shift the cams to such a position that the suction spare cam 223 and the push button spare cam 226 line up with lever 258 and arm 272, respectively.

This shifting is done during the end portion of the strike cycle after a new set of pins is deposited

on the alley by the table T and during the time the latter ascends again. The shifting of the hub 221, on which all cams are mounted, occurs automatically after the protruding plunger 214 leaves cam arm 237 and the pressure exerted by spring 231 tends to push the cams back to their original positions, but the position is controlled by the arm 248, the hook end 249 of which swings into the path of a stud 308 (Figures 9, 10 and 12) protruding from the cam arm 237, thereby locking the latter and determining the position of the cams. In order to maintain the proper sequence of operation of the machine at all times, the suction spare cams 223 and 224, as well as the push button spare cams 226 and 227 are alternated each time after a "strike" is made. As long as no "strike" is made no cams will be shifted.

Arm 248 provided with the hook portion 249 is actuated by the cam lever 246 carrying the cam follower 245 which contacts the star cam 244. The latter, as mentioned heretofore, is attached to the star wheel 243 which is actuated by the protruding plunger 214 as it slides along the edge of cam arm 237 and comes in contact and engages the teeth of the star wheel. Of course, it is understood that the latter can only be turned one tooth at a time and the position of cam follower 245 on star cam 244 determines the position of the hook portion 249 of arm 248, it is brought either into or out of the path of stud 308 on arm 237 depending on the alternating positioning of the cams mentioned above.

After the protruding plunger leaves cam arm 237, the head of the plunger engages with a stationary cam segment 310 (Figures 10 and 13) which pushes it back to its original or locked position in hub 218 of gear 212 and its corresponding pawl 215 engages again in recess 216 of stem 217 and keeps said plunger locked until a strike is registered and pawl 215 is tripped again by the segmented portion 216 of bell crank lever 275. The stationary cam segment 310 protrudes from the inner wall of housing 201. In order to assure proper locking of pawl 215 in recess 216, each pawl is in contact with a small spring mounted plunger 312 (Figure 13) which has the tendency of keeping each pawl in constant contact with its corresponding stem. Each stem 217 is provided with a stop collar 314 which checks the protruding movement of its corresponding plunger when its pawl is tripped.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a bowling pin setting machine, a magazine containing a number of inverted bowling pins sufficient for playing, a plurality of pin handling cups located adjacent said magazine, positively actuated movable means for transferring said pins from said magazine and positioning them head end upright in said cups, and means for transferring said pins head ends upright to an alley.

2. In a bowling pin setting machine having a magazine constructed and arranged to hold a number of inverted bowling pins in an aligned series, a plurality of pin handling cups movable into and out of alignment adjacent said magazine, means for transferring said aligned series of pins from said magazine and positioning said

pins head end upright in said cups when said cups are located adjacent said magazine, means for moving each of said cups out of alignment and positioning the same in substantially triangular formation, and means for transferring pins to an alley.

3. In a bowling pin setting machine having a magazine constructed and arranged to hold a plurality of vertically positioned bowling pins, a plurality of individually operable pin transferring cup members adapted to hold bowling pins handle end upright, means for moving said members into and out of pin receiving position adjacent said magazine, means for simultaneously transferring said plurality of vertically positioned pins from said magazine into said members, means mounting said members for generally converging movement away from said magazine, and means for moving said members individually and differentially with pins held upright therein into substantially triangular playing formation for delivery to an alley.

4. A bowling pin setting machine comprising a magazine, means for collecting and supporting a plurality of pins stationary in said magazine, a plurality of aligned pin handling cups located adjacent said magazine, means for transferring a number of pins sufficient for playing from said aligned pins in said magazine and positioning said pins head end upright in said cups, a pin setter, and separately operating means for moving each of said cups to deliver said pins to said setter.

5. A bowling pin setting machine comprising a magazine, means for aligning a plurality of pins in said magazine, a plurality of aligned pin handling cups located adjacent said magazine, means for simultaneously transferring a number of pins sufficient for playing from said magazine and positioning said pins handle end upright in said cups, a pin setter, means for moving said cups to dispose the pins located therein handle end upright in substantially playing positions beneath said pin setter, means for effecting relative movement between said pins and setter to deliver said pins to said setter, means for returning said cups to pin receiving position adjacent said magazine, and means for moving said setter to place said pins on said alley.

6. A bowling pin setting machine comprising a magazine, means for aligning a plurality of inverted pins in said magazine, a plurality of aligned pin handling cups located adjacent said magazine, means for simultaneously transferring a number of pins sufficient for playing from said aligned inverted pins in said magazine and positioning said transferred pins handle end upright in said cups, a pin setter, means for moving said cups to locate the pins carried thereby in substantially playing positions handle end upright beneath said pin setter, means for effecting relative movement between said pins and setter to deliver said pins to said setter, and means for moving said setter to place said pins on said alley.

7. A bowling pin setting machine comprising a magazine, a pin setter provided with a plurality of triangularly arranged pin holders, and mechanism for delivering a set of pins handle end upright from said magazine and positioning the same in a corresponding triangular arrangement beneath said holders on said setter, said mechanism comprising a support, guides on said support, a plurality of slidable rack driven members each having one end thereof generally con-

- vergingly mounted for sliding movement in said guides, pin supporting cups fixed to said ends of said members, pinions mounted to engage each of said racks on said members, a drive shaft, driving connections between said shaft and said pinions, and means for driving said shaft to effect a differential and individual movement of each of said cups.
8. A bowling pin setting machine comprising a magazine, means for delivering inverted pins to said magazine, a pin setter, a transfer device for delivering upright pins to said setter, transfer conveying mechanism constructed and arranged to engage the heads of inverted pins in said magazine, and means for operating said mechanism to move said inverted pins out of said magazine and deliver them upright into said device.
9. A bowling pin setting machine comprising a magazine, means for delivering inverted pins to said magazine, a pin setter, a transfer device for delivering upright pins to said setter, transfer conveying mechanism constructed and arranged to engage the heads of inverted pins in said magazine, means for operating said mechanism to move said inverted pins out of said magazine and into said device, and a guide for directing said pins upright into said device.
10. A bowling pin setting machine comprising a magazine, means for delivering inverted pins to said magazine, a pin setter, a transfer device for delivering upright pins to said setter, transfer conveying mechanism constructed and arranged to engage the heads of inverted pins in said magazine, means for operating said mechanism to move said inverted pins out of said magazine and into said device, and a stationary U-shaped guide through which said pins are moved for locating said pins upright in said device, said stationary guide being provided with a plurality of openings through which pins move to said setter.
11. A bowling pin setting machine for use with an alley having a pin supporting bed, a pin magazine having means for assembling an aligned row of inverted bowling pins, pin handling cups equal in number to the number of pins required for playing movable into alignment adjacent said magazine, and means for placing a bowling pin handle end upright in each of said cups, including means for engaging from handle end of each inverted pin and transferring each of said pins from said magazine into one of said cups.
12. In a bowling pin setting machine for use with a bowling alley, a magazine for bowling pins, means for assembling in said magazine at least the number of pins required for a given setting, a pin setter provided with a plurality of individually moveable setter-resetter units loosely mounted on said setter for laterally shifting movement and constructed and arranged to be located in substantially triangular arrangement on said setter, devices located beneath said magazine for receiving pins in upright position from said magazine, means for moving said devices from pin receiving position to pin delivery position corresponding to the arrangement of said units adjacent said setter, and selectively operated means for operating said units to cause the same to hold and release pins to be positioned on said alley.
13. In a bowling pin setting machine, a magazine for bowling pins, means for assembling in said magazine at least the number of pins required for a given setting, a pin setter, devices located beneath said magazine for receiving pins in handle end upright position from said maga-
- zine, means for simultaneously transferring said assembled pins in said magazine to said devices, means for moving said devices from pin receiving position to pin delivery position adjacent said setter with said handle ends of said pins positioned for delivery to said setter, and means for effecting relative movement between said setter and devices to remove said pins from said devices for delivery by said setter to an alley.
14. In a bowling pin setting machine, a magazine for bowling pins, means for assembling in said magazine an aligned row of vertically positioned bowling pins equal in number at least to the number of pins required in a given setting, a pin setter, pin handling devices movable into pin receiving position adjacent said magazine for receiving pins therefrom and holding the same handle end upright, means for simultaneously transferring said assembled pins in said magazine to said devices, mechanism for moving said devices from said aligned position to a pin delivery station adjacent said setter, said mechanism including means for imparting differential movement to said devices to dispose them in substantially triangular arrangement beneath said setter, and means for effecting relative movement between said setter and devices to effect the delivery of said pins from said devices to said setter.
15. In a bowling pin setting machine, a magazine for bowling pins, means for assembling in said magazine at least the number of pins required for a given setting, a pin setter, pin transfer devices movable from a pin receiving position adjacent said magazine to a pin delivery position adjacent said setter, means for removing the number of pins required for a setting from said magazine and locating said pins handle end upright in said devices, and positively and differentially operating means for moving each of said filled devices from said receiving position to delivery position beneath said setter.
16. Pin handling mechanism for a bowling pin setting machine comprising, spaced pin supporting members holding a plurality of inverted pins, a transfer conveyor for conveying upright pins from said members, an inverting device movable into engagement with said inverted pins, a stationary inverted generally U-shaped pin turning chute positioned between said members and conveyor, and means for moving said device to remove said pins from between said members and locate the same upright in said conveyor.
17. Pin handling mechanism for a bowling pin setting machine comprising spaced pin supporting members, means for feeding a predetermined number of inverted pins to said members, a plurality of pin conveyors positioned to receive pins from said members, pin turning guides mounted for guiding pins from said members and into said conveyors, and means movable into engagement with said inverted pins for moving them through said guides for delivery upright in said conveyors.
18. Pin handling mechanism for a bowling pin setting machine comprising, a pin setter, a magazine including, means for assembling and storing a plurality of inverted pins, a conveyor movable between said magazine and setter, means for delivering a plurality of pins to said conveyor, and means for turning said pins while they are being delivered to said conveyor in upright position.
19. In a bowling pin setting machine, a pin setter, a magazine including spaced means for supporting a predetermined number of inverted pins, a plurality of differentially movable pin convey-

ors movable between said magazine and said setter, means for delivering individual pins into each of said conveyors, and means for turning said pins to position the same in upright condition in said conveyors.

20. In a bowling pin setting machine, a pin setter, a magazine for supporting a predetermined number of bowling pins, conveying mechanism for transferring pins from said magazine to said setter comprising, a plurality of cups each constructed and arranged to support the butt end of a bowling pin with the handle end thereof in normal upright position, a traveling member mounting each cup, and driving mechanism associated with each of said members for imparting thereto individual and differential movement to position said cups and pins in normal upright position therein in substantially triangular formation relative to said setter.

21. In a bowling pin setting machine, a pin setter, a magazine for supporting a predetermined number of bowling pins, conveying mechanism for transferring pins from said magazine to said setter comprising, a plurality of cups each constructed and arranged to support a bowling pin handle end upright, a traveling member mounting each cup, a rack fixed to each member, guides constraining said members to move in a generally horizontal plane, pinions engaging each of said racks, and driving means associated with each of said pinions for imparting thereto individual and differential movement to position said cups and upright pins therein in substantially triangular formation relative to said setter.

22. In a bowling pin setting machine, a pin setter, a magazine including spaced means for supporting a predetermined number of inverted pins, a plurality of differentially movable pin conveyors movable between said magazine and said setter, a pin turning chute located adjacent said magazine, and means for moving pins through said chute for delivery upright into said conveyors.

23. In a bowling pin setting machine for use with a bowling alley, a pin setter, a magazine including spaced means for supporting a predetermined number of bowling pins, a plurality of differentially movable pin conveyors constructed and arranged to support pins handle end upright positively and differentially operating means for moving each of said conveyors between said magazine and said setter, means for delivering a set of pins handle end upright into said conveyors, and selectively operated control mechanism operative as the result of the removal of all pins from the alley as the result of the throwing of the first ball of a frame or the throwing of the second ball for setting into operation said last named means and said means for operating said conveyors to feed pins from said magazine to said setter.

24. In a bowling pin setting machine, a magazine including means for storing a predetermined number of pins butt end upward, a pin setter mounted for movement to and from an alley bed for setting and resetting bowling pins thereon in playing arrangement, a plurality of conveyors for delivering upright bowling pins from said magazine to said setter, said conveyors being movable beneath said magazine and setter to receive pins from said magazine and deliver the same to said setter, a stationary curved pin turning guide located adjacent said magazine, and means for removing pins from said magazine and projecting

the same through said guide for delivery in upright condition to said conveyors.

25. A bowling pin setting machine for use with a bowling alley comprising, mechanism for assembling a plurality of bowling pins butt end upward, means for removing a set of pins from said assembly corresponding to the number of pins required for a new frame, means for inverting each of said selected pins, conveyor means for transferring said upright pins away from said inverting means and positioning the same in playing arrangement above said alley, a device provided with a plurality of triangularly arranged holders for holding said upright pins for setting in playing position on said alley, means for lowering said device to position said pins on said alley, means for releasing said pins from said holders, means to raise said device and leave said pins standing on said alley prior to the throwing of the first ball, and selective control mechanism operative after said first ball has been thrown and all or some pins have been knocked down thereby for reconstituting the operation of said device and holders to set a new frame of pins or cause said holders to lift and reset any pins left standing for the throwing of the next ball.

26. A bowling pin setting machine for use with a bowling alley comprising, mechanism for assembling a plurality of bowling pins butt end upward, means for removing a set of pins from said assembly corresponding to the number of pins required for a new frame, means for inverting each of said pins, conveyor means for transferring said upright pins away from said inverting means and positioning the same in playing arrangement above said alley, and a device having a plurality of pin setting units for setting said upright pins on said alley, said units also being operative to reset any pins remaining standing on said alley after the throwing of a ball.

27. A bowling pin setting machine for use with a bowling alley comprising, mechanism for assembling a plurality of bowling pins butt end upward, means for removing a set of pins from said assembly corresponding to the number of pins required for a new frame, means for inverting each of said selected pins, conveyor means for transferring said upright pins away from said inverting means and positioning the same in playing arrangement above said alley, a device having a plurality of laterally movable pin holding and setting units, means for effecting relative movement between said conveyor means and said device to effect a delivery of pins from said conveyor means to said units, and means for moving said device to deposit said upright pins on said alley.

28. A bowling pin setting machine for use with a bowling alley comprising, mechanism for assembling a plurality of bowling pins butt end upward, means for removing a set of pins from said assembly corresponding to the number of pins required for a new frame, means for inverting each of said selected pins, conveyor means for transferring said upright pins away from said inverting means and positioning the same in playing arrangement above said alley, a device having a plurality of laterally movable pin holding and setting units, means for effecting relative movement between said conveyor means and said device to effect a delivery of pins from said conveyor means to said units, means for moving said device to deposit said upright pins on said alley, and means operative after the throwing of a ball for operating said units to

reset in their on or off-spot position any pins remaining standing after the throwing of said ball.

29. A bowling pin setting machine for use with a bowling alley comprising, mechanism for assembling a plurality of bowling pins butt end upward, means for removing a set of pins from said assembly corresponding to the number of pins required for a new frame, means for inverting each of said selected pins, conveyor means for transferring said upright pins away from said inverting means and positioning the same in playing arrangement above said alley, a device having a plurality of laterally movable pin holding and setting units for setting and resetting on-spot and off-spot pins, means for effecting relative movement between said conveyor means and said device to effect a delivery of pins from said conveyor means to said units, means for moving said device to deposit said upright pins on said alley, and selective means for controlling said conveyor means to furnish a new set of upright pins to said device if all pins on said alley or knocked down by the first ball thrown.

30. A bowling pin setting machine for use with a bowling alley comprising, mechanism for assembling a plurality of bowling pins butt end upward, means for removing a set of pins from said assembly corresponding to the number of pins required for a new frame, means for inverting each of said selected pins, conveyor means for transferring said upright pins away from said inverting means and positioning the same in playing arrangement above said alley, a device having a plurality of laterally movable pin holding and setting units for setting and resetting on-spot and off-spot pins, means for effecting relative movement between said conveyor means and said device to effect a delivery of pins from said conveyor means to said units, means for moving said device to deposit said upright pins on said alley, selective means for controlling said conveyor means to furnish a new set of upright pins to said device if all pins on said alley are knocked down by the first ball thrown, or render said conveyor means inactive to furnish a new set of pins, and means coacting therewith to cause said units to reset on the alley in their on or off-spot position any pins remaining standing after the throwing of a ball.

31. In a bowling pin setting machine for use with a bowling alley, mechanism for assembling a plurality of bowling pins butt end upward, a pin setter, a pin inverter, conveyor cups operable to receive pins delivered from said mechanism, means for operating said inverter to eject pins from said mechanism for delivery upright into said cups, and selective means to operate said cups and setter to set a new frame of pins or reset standing pins on said alley after a ball has been thrown.

32. In a bowling pin setting machine for a bowling alley having a pin supporting bed, a pin setter, pin handling units loosely mounted on said setter, a pin conveying mechanism movable from a pin receiving position to a delivery position beneath said setter for delivery of a set of pins handle end upright to said pin handling units, means for moving said setter to deposit pins held by said units on said alley bed in on-spot position, selective mechanism for causing said setter to move to and from said alley bed to cause said same units to lift any pins remaining standing after a ball has been thrown and

50 reset said pins in exact on or off-spot positions or set a new frame of pins if all pins are knocked down by the first ball thrown.

33. In a bowling pin setting machine for use with a bowling alley, a pin setter, pin holding units for setting and resetting pins loosely mounted on said setter, a pin conveyor provided with a plurality of holders for conveying pins handle end up for delivery to said setter, means for effecting relative movement between said setter and said holders for transferring pins from said holders to said units, means for moving said setter with said pins to deposit the same in playing arrangement on said alley, and means operative after a ball has been thrown for again moving said setter adjacent said alley for causing said units to lift and re-set in on or off-spot position any pins remaining standing.

34. In a bowling pin setting machine for use with a bowling alley, a pin setter, pin holding units for setting and resetting pins loosely mounted on said setter, a pin conveyor provided with a plurality of holders for conveying pins handle end up for delivery to said setter, means for effecting relative movement between said setter and said holders for transferring pins from said holders to said units, means for moving said setter with said pins to deposit the same in playing arrangement on said alley, and selective means operative in response to the number of pins knocked down by a ball thrown for setting a new frame of pins or causing said setter-resetter units to reset in the same on or off-spot positions any pins which remained standing as a result of the ball thrown.

35. In a bowling pin setting machine for a bowling alley, a pin setter, a plurality of movably mounted pin setting and resetting pin holding units carried by said setter, pin conveying devices for conveying bowling pins handle end upright, means for moving said devices into exact playing arrangement relative to said units for delivery of said pins to said units, and means for effecting relative movement between said units and devices to align said units for receiving said pins delivered thereto by said devices.

36. In a bowling pin setting machine for a bowling alley, a pin setter movable vertically to and from said alley, a plurality of movably mounted pin setting and resetting pin holding units carried by said setter, pin conveying devices for conveying bowling pins handle ends upright, means for moving said devices into exact playing arrangement relative to said units above said alley and beneath said setter for delivery of said pins to said units, means for effecting relative movement between said units and devices to align said units for receiving said pins, and means operative after said pins have been delivered to said aligned units for returning said devices to pin receiving position.

37. In a bowling pin setting machine for a bowling alley, a pin setting table, individually movable pin setting and resetting gripping units carried by said table, a conveyor device including, a plurality of pin holders corresponding in number to that of said units, and means for moving said holders from a pin receiving station to a pin delivering station beneath said units, means for moving said holders into triangular arrangement during their travel from said receiving to said delivering station, means for moving said table downward to cause said units to engage and hold the handle ends of said pins carried upright in said holders, and means on said units for caus-

ing said units to move into axial alignment with said pins in said holders.

38. A bowling pin setting machine for use with a bowling alley, comprising a pin assembling station, a pin setter table, a plurality of setter units mounted for individual movement thereon, and normally positioned in substantially pin playing arrangement thereon, mechanism operative beneath said table for conveying a predetermined number of pins handle ends upright from said assembly station and positioning them in said movable setters for delivery to said alley, and means for maintaining said pins handle end upright after they have been delivered to said table and until said pins are positioned on said alley. 10

39. A bowling pin setting machine for use with a bowling alley, comprising a pin assembling station, a pin setter table, a plurality of setter units mounted for individual movement thereon, and normally positioned in substantially pin playing arrangement thereon, a plurality of individually movable pin conveyors for moving pins handle ends upright from said station to a delivery position beneath said table, means for locating said conveyors in exact pin playing position relative to said units beneath said table, means for effecting relative vertical movement between said setter and conveyors to cause the handle ends of said pins in said conveyors to move any out-of-position units into axially aligned relationship with said pins, and means for operating said units to grip and hold said pins. 20

40. A bowling pin setting machine for use with a bowling alley, comprising a pin assembling station, a pin setter table, a plurality of setter units mounted for individual movement thereon, and normally positioned in substantially pin playing arrangement thereon, a plurality of individually movable pin conveyors for moving pins handle ends upright from said station to a delivery position beneath said table, means for locating said conveyors in exact pin playing position relative to said units beneath said table, means for effecting relative vertical movement between said setter and conveyors to cause the handle ends of said pins in said conveyors to move any out-of-position units into axially aligned relationship with said pins, means for operating said units to grip and hold said pins, means for separating said setter and pins held therein from said conveyors, means for returning said conveyors to pin receiving position, and means for lowering and raising said table to set and reset said pins. 30

41. A bowling pin setting machine for use with a bowling alley, comprising a pin assembling station, a pin setter table, a plurality of suction setter units mounted for individual movement thereon, and normally positioned in substantially pin playing arrangement thereon, a plurality of individually movable pin conveyors for moving pins handle ends upright from said station to a delivery position beneath said table, means for locating said conveyors in exact pin playing position relative to said units beneath said table, means for effecting relative vertical movement between said setter and conveyors to cause the handle ends of said pins in said conveyors to move any out-of-position units into axially aligned relationship with said pins in said conveyors, means for operating said units to grip and hold said pins, means for separating said setter and pins held therein from said conveyors, means for returning said conveyors to pin receiving position, means for lowering and raising said table to set and reset said pins, and means for controlling the suction 40

in said units to cause the same to hold or release pins dependent upon the effect desired as the result of each ball thrown.

42. A bowling pin setting machine for use on a bowling alley comprising, a pin assembling station, a pin setter table movable to and from said alley for setting and resetting pins thereon, a plurality of pin setting and resetting units carried by said table and mounted for limited movement thereon, said units being arranged generally in pin playing arrangement on said table, conveying mechanism for delivering pins handle ends upright to each of said units including, individual pin holder cups corresponding in number to said units, and means for imparting differential movement to each of said cups to locate said cups and pins carried handle end upright therein in triangular pin playing position beneath said table and said movable units. 15

43. A bowling pin setting machine for use on a bowling alley comprising, a pin assembling station, a pin setter table movable to and from said alley for setting and resetting pins thereon, a plurality of suction pin setting and resetting units carried by said table and mounted for limited movement relative thereto, said units being arranged generally in pin playing arrangement on said table, conveying mechanism for delivering pins handle ends upright to each of said units, including individual pin holder cups corresponding in number to said units, positively actuated means for imparting differential movements to each of said cups to locate said cups and pins carried handle end upright therein in triangular pin playing position beneath said table and said movable units, and selective means for creating suction in said units to cause said units to grip said pins and hold the same for setting and resetting on said alley. 25

44. A bowling pin setting machine for use with a bowling alley comprising, a pin assembling station, a pin setter table, a plurality of setter units mounted for individual movement thereon, and normally positioned in substantially pin playing arrangement thereon, means for delivering a predetermined number of pins handle ends upright from said assembly station and positioning them in said movable setters, and means operative when said pin handles have been disposed in said units for gripping and supporting said pins with the butt ends free and projecting downwardly towards said alley. 35

45. A bowling pin setting machine for use with a bowling alley comprising, a pin assembling station, a pin setter table, a plurality of suction setter units mounted for individual movement thereon, and normally positioned in substantially pin playing arrangement thereon, a plurality of individually movable pin conveyors for moving pins handle ends upright from said station to a delivery position beneath said table, driving means for moving and locating each of said conveyors in exact pin playing position beneath said table, means for effecting relative vertical movement between said setter and conveyors to cause the handle ends of said pins in said conveyors to move any out-of-position units to move into axially aligned relationship with said pins, and control means for creating suction in each of said units to grip and hold said pins. 40

46. In a bowling pin setting machine for setting pins on an alley bed in playing position, a pin magazine comprising, a plurality of aligned pin holding elements, means for placing butt ends of pins in said elements with the handle ends thereof 50

projecting upwardly therefrom, means for moving each of said elements individually with said pins handle end upright therein from aligned position into substantial triangular pin playing position, a pin spotting and respotting device, pin gripping members carried by said device and constructed and arranged to receive the handle ends of said upright pins, means for moving said device relative to said elements to grip the head ends of pins positioned in said elements with the free butt ends extending downwardly towards said alley bed, means for returning said elements to said magazine, means for lowering said device relative to said alley bed to position said pins on said bed in playing position, and means operative after the throwing of the first ball to accommodate said device for gripping standing pins either on or off-spot and resetting the same on said bed.

47. In a bowling pin setting machine, mechanism for setting and resetting pins in upright position and in playing arrangement upon the bed of a bowling alley comprising, an elevator, means mounting said elevator for straight line movement only to and from said alley, a single set of individually moveable pin holders positioned in generally playing arrangement upon said elevator, means for moving said elevator with pins held in said holders to locate said pins on said alley, means for releasing said pins from said holders, means for raising said elevator above said alley prior to the throwing of the first ball, means for lowering said elevator to position said same holders for engagement with any pins remaining standing after the throwing of said first ball and cause such standing pins to shift the particular moveable holders designed to lift such pins into substantial alignment with the longitudinal axis of such pins to be lifted, means for energizing said holders to grip any pins remaining standing, means for raising said elevator whereby said holders lift said standing pins above said alley, means for again lowering said elevator to reposition said lifted pins in the exact on or off-spot position each occupied before being lifted, means for releasing said pins from said holders, and means for again raising said elevator above said alley.

48. A pin setting and resetting device for use with a pin setting machine comprising a table movable to and from a bowling alley, a single set of generally triangularly disposed suction operated pin setting-resetting units carried by said table, an apertured support mounting said units, means for delivering a set of pins to said units, means for moving said table to and from an alley to deposit said pins thereon, and suction control means operative in response to the results obtained by a thrown ball for controlling the introduction of suction into said units for setting a new frame of pins on said alley or resetting some of the same frame remaining standing on the alley after the throwing of a first ball.

49. A pin setting and resetting device for use with a pin setting machine comprising a table movable to and from a bowling alley, a single set of generally triangularly disposed individually movable pin setting-resetting units carried by said table, an apertured support mounting said units, means mounted beneath said table for delivering a set of pins to said units, means for operating said units to grip the head ends of pins delivered thereto, means for moving said table to and from an alley to deposit said pins thereon, and control means operative in response to the results obtained by a thrown ball for operating said units

50. In a bowling pin setting machine, a pin setting table, means for moving said table to and from an alley to set and reset pins thereon, a plurality of generally triangularly disposed pin setting-resetting units carried by said table, supporting means carried by said table mounting said units for limited movement thereon, and a plurality of individually and differentially movable conveyors for feeding a set of pins handle end upright to said units for transfer in playing arrangement on said alley.

51. A pin inverting device for a bowling pin setting machine having a magazine provided with means for supporting pins in inverted position comprising, an inverted U-shaped chute, a device for engaging the handle ends of inverted pins, and means for moving said device to eject said pins from said magazine and propel them through said chute for discharge therefrom in upright position.

52. A pin inverting device for use in a bowling pin setting machine having a magazine provided with spaced members for supporting an aligned row of bowling pins comprising, an elongated pin turning chute located adjacent said magazine, and means constructed and arranged to engage said inverted pins and eject them from said magazine for gravity delivery therefrom in upright position.

53. A pin inverting mechanism for a bowling pin setting machine comprising, an elongated U-shaped pin inverting chute provided with two depending legs, means for supporting said chute in pin inverting position, and means for forcing inverted pins upright through one of said legs for gravity discharge in upright position through the other of said legs.

54. A pin inverting mechanism for a bowling pin setting machine comprising, an elongated U-shaped pin inverting chute provided with two depending legs, a plurality of inwardly extending vanes coacting to space and position pins inverted by said chute, means for supporting said chute in pin inverting position, and means for forcing inverted pins upwardly through one of said legs for gravity discharge between said vanes in upright position through the other of said legs.

55. A pin inverting mechanism for a bowling pin setting machine comprising, an elongated U-shaped pin inverting chute provided with two depending legs, a plurality of inwardly extending vanes coacting to space and position pins inverted by said chute, means for supporting said chute in pin inverting position, means for forcing inverted pins upwardly through one of said legs for gravity discharge between said vanes in upright position through the other of said legs, and pin discharge openings formed in said last-named leg of said chute for removal of upright pins therethrough.

56. Pin inverting mechanism for use with a bowling pin setting machine having an elongated magazine constructed and arranged to support a plurality of aligned inverted substantially vertical upright bowling pins comprising a complementary stationary pin inverting chute extending along and in operative arrangement with said magazine, and means for moving pins from said magazine through said chute for gravity discharge therefrom in upright position.

57. Pin inverting mechanism for use with a

bowling pin setting machine having an elongated magazine constructed and arranged to support a plurality of aligned inverted substantially vertical upright bowling pins comprising a complementary stationary pin inverting chute including two depending legs, one of said legs being located above said magazine, the other of said legs being provided with a plurality of inwardly extending vanes for spacing and guiding pins moving therethrough, and means for moving a plurality of pins in a number sufficient to meet the requirement of a given frame from said magazine into said first-named leg of said chute for discharge butt end down between said vanes in said last-named chute.

58. In a bowling pin setting machine, a pin setting and resetting table movable to and from an alley, a plurality of pin gripping setter-resetter units mounted on one side of said table, a cam shaft, a plurality of gripping unit control cams carried on said shaft, strike and spare control cams also carried on said shaft, and selectively operated means operable as a result of all pins of

10 a frame being knocked down by the first ball or the failure of said first ball to knock down all said pins, to select certain of said gripper unit control cams and said strike cam or said spare cam for controlling the operation of said units for setting of a new set of pins or resetting pins remaining standing after the first ball has been thrown.

59. Control mechanism for a bowling pin setting machine having a traveling pin setting-resetting table and a plurality of suction operated pin gripper setter-resetter units mounted on one side of said table comprising, a cam shaft, means for driving said cam shaft, a plurality of suction control cams mounted on said shaft, strike and spare cams also mounted on said shaft, and control means operable in response to the removal of all pins by the first ball thrown or only a part of said pins by said first ball for selecting certain of said suction means and said strike or spare cams for controlling the operation of said units for setting a new frame of pins or resetting pins left standing after the throwing of said first ball.

RUPERT E. RUNDELL.

CERTIFICATE OF CORRECTION.

Patent No. 2,388,709.

November 13, 1945.

RUPERT E. RUNDELL.

It is hereby certified that error appears in the printed specification of the above numbered patent requiring correction as follows: Page 10, first column, line 50, claim 11, for the word "from" read --the--; page 12, first column, line 24, claim 29, for "or knocked" read --are knocked--; and that the said Letters Patent should be read with this correction therein that the same may conform to the record of the case in the Patent Office.

Signed and sealed this 26th day of February, A. D. 1946.

bowling pin setting machine having an elongated magazine constructed and arranged to support a plurality of aligned inverted substantially vertical upright bowling pins comprising a complementary stationary pin inverting chute including two depending legs, one of said legs being located above said magazine, the other of said legs being provided with a plurality of inwardly extending vanes for spacing and guiding pins moving therethrough, and means for moving a plurality of pins in a number sufficient to meet the requirement of a given frame from said magazine into said first-named leg of said chute for discharge butt end down between said vanes in said last-named chute.

58. In a bowling pin setting machine, a pin setting and resetting table movable to and from an alley, a plurality of pin gripping setter-resetter units mounted on one side of said table, a cam shaft, a plurality of gripping unit control cams carried on said shaft, strike and spare control cams also carried on said shaft, and selectively operated means operable as a result of all pins of

10 a frame being knocked down by the first ball or the failure of said first ball to knock down all said pins, to select certain of said gripper unit control cams and said strike cam or said spare cam for controlling the operation of said units for setting of a new set of pins or resetting pins remaining standing after the first ball has been thrown.

59. Control mechanism for a bowling pin setting machine having a traveling pin setting-resetting table and a plurality of suction operated pin gripper setter-resetter units mounted on one side of said table comprising, a cam shaft, means for driving said cam shaft, a plurality of suction control cams mounted on said shaft, strike and spare cams also mounted on said shaft, and control means operable in response to the removal of all pins by the first ball thrown or only a part of said pins by said first ball for selecting certain of said suction means and said strike or spare cams for controlling the operation of said units for setting a new frame of pins or resetting pins left standing after the throwing of said first ball.
